(57) CLAIM

The ornamental design for a minimalist outsole as shown and described.

DESCRIPTION

FIG. 1 is a medial view of a minimalist shoe outsole in accordance with the present invention;

FIG. 2 is a lateral view thereof;

FIG. 3 is a top view thereof; and,

FIG. 4 is a bottom view thereof.

The short-dash broken lines depict portions of the minimalist outsole that form no part of the claimed design, and the long-dash broken lines are included for the purpose of illustrating the bounds of the claimed design and also form no part of the claimed invention.

1 Claim, 4 Drawing Sheets
